UNITED STATES PATENT OFFICE.

JESSE C. SIMMONS, OF SHELBY, MICHIGAN.

WASHING-MACHINE.

No. 926,776.

Specification of Letters Patent.

Patented July 6, 1909.

Application filed April 20, 1908. Serial No. 428,094.

To all whom it may concern:

Be it known that I, JESSE C. SIMMONS, a citizen of the United States, and a resident of the city of Shelby, Oceana county, Michigan, have invented certain new and useful Improvements in Washing-Machines; and I do hereby declare that the following is a full, clear, and exact description of the same, reference being had to the accompanying drawings, and to the letters of reference thereon, which form a part of this specification.

Of the many various types of washing machines heretofore constructed, many have been rotary in their character. Some have been oscillating, to afford a rubbing action on the articles to be washed and a few have been reciprocating. In practice, in all of these there has been, to a greater or less extent, a rubbing action which serves no doubt, to some extent to loosen the dirt, but as well, wears the rolls and tears the articles being washed, frequently ruining or destroying the more delicate fabrics subjected to such treatment. In consequence the more delicate fabrics are practically always washed by hand to prevent injury.

The object of this invention is to afford a vertically reciprocating washer, whereby the water is forced back and forward through the fabrics treated, in one direction at least being forced by water pressure.

It is also an object of the invention to afford a reciprocating receptacle for the washer constructed of reticulated material, though which the water readily passes in any direction and in which a cover of reticulated material is provided above the fabric to more or less confine the same in the receptacle during the washing operation.

The invention consists in the matters hereinafter described and more fully pointed out and defined in the appended claims.

In the drawings: Figure 1 is a central vertical section of a device embodying my invention. Fig. 2 is a section taken at a right angle therewith. Fig. 3 is an enlarged detail of a part of the frame for supporting the rinsing tub. Fig. 4 is a fragmentary detail of the same.

As shown in the drawings: A galvanized iron tub A, conveniently cylindric in form, is supported upon legs a, which are riveted thereto in the side thereof and are constructed of strips of steel which may be flat bars or any suitable structural form and extend downwardly a suitable length to support the

tub at the desired height, and then are bent upwardly and engaged to the bottom of the tub centrally thereof by bolts a², which also pass through the base B, of the hanger 60 whereby the actuating mechanism is secured on the bottom of the tub. As shown, said legs are four in number and the inwardly inclined portion a' thereof affords a strong brace affording great rigidity. Said hanger, 65 as shown, comprises a base portion B, before mentioned and a downwardly extending bracket b, having a head b' thereon, which projects inwardly to a point beneath the middle of the tub and through which extends the 70 actuating shaft C, which, as shown, is provided with a transverse, horizontal slotted extension or yoke c. Said shaft extends upwardly through the bottom of the tub and as shown, the aperture through the hanger is 75 closed by means of a suitable gland c', indicated in Fig. 2 and a suitable gland may be provided in the bottom of the tub around the shaft. Rigidly secured on said shaft within the tub, is a spider D, having any desired 80 number of arms, and which is secured in the bottom of the reticulated basket D', adapted to be reciprocated in the tub vertically by means of said shaft and spider. Fitted in the basket and adapted to be removably engaged on the upper end of a shaft C, is a reticulated cover D², which serves to confine the fabrics treated in the bottom of the basket but permits the free flow of water therethrough. A close fitting cover d, is provided 85 to entirely close the tub A, to confine the steam or vapor thereto. Said basket is reciprocated as follows: A horizontal shaft E, is journaled in the bracket hanger b, in a suitable fitting or bracket e, bolted on one of the 90 legs of the tub and is provided on its inner end adjacent the shaft C, with a disk e', provided with a crank pin e², which fits in the transverse slot or yoke c, in the shaft C. At 95 its outer end said shaft is provided with a beveled pinion e³, which meshes with a corresponding beveled pinion e⁴, on a vertical shaft E', journaled in an outwardly directed bracket arm e⁵, at its lower end and at its upper end in a bracket e⁶. At its upper end 100 said shaft is also provided with a bevel gear e⁷, with which meshes a bevel pinion e⁸, on the end of a shaft e⁹, which is journaled in an upwardly turned end e¹⁰ of the bracket e⁶. On its outer end said shaft e⁹ is provided with 105 a balance wheel F, provided with a handle or crank f, whereby the same may be rotated.

If desired, an auxiliary bench or frame may be provided on which may be supported the rinsing tub or other receptacle. For this purpose, suitable brackets G, are secured 5 to the legs a, of the tub, conveniently on the side opposite the wheel F, and adapted to engage therein are straps g, having hooked ends for such engagement and a downwardly turned, transversely slotted end g', adapted 10 to receive the inwardly directed hooked end g² of the leg G'. Of course, other horizontal members g, may be arranged either parallel or transversely said horizontal member g, before described.

15 The operation is as follows: In rotating the crank wheel F, the basket D', with the fabric therein and confined by the cover D², is reciprocated up and down at a sufficient rate of speed to draw the water (which should 20 be sufficient to cover the reticulated cover D² and the basket at its lowest point) through the cover, fabric and bottom. The partial vacuum produced by the upward movement of the basket and its contents greatly assists 25 in forcing the water therethrough and in the same manner the downward movement serves to confine the water beneath the basket and the fabric therein and serves to positively force the fluid in the opposite direction 30 through the fabric. The extent of the reciprocation, of course, depends upon the throw of the crank pin e² on the disk e', and the reciprocations need not necessarily 35 be rapid. In consequence, of course, the power developed with the hand wheel F, may be multiplied in any familiar manner by the successively smaller or larger pinions or in any other suitable manner.

Inasmuch as the entire construction is 40 metallic and galvanized or otherwise treated to render the same rust proof, a washing machine constructed as described will last indefinitely. Furthermore, the structural steel legs, which serve not only to support the tub 45 and its contents but as well to rigidly brace the same at the center from the bottom afford great strength and durability and serve as satisfactory means for attaching thereto the auxiliary frame or bench for supporting 50 another tub or other receptacle.

Of course, I am aware that details of the construction may be varied. I therefore do not purpose limiting this application for patent otherwise than necessitated by the prior 55 art.

I claim as my invention:

1. A washing machine embracing a tub, a reticulated basket therein fitting loosely

thereto, a shaft extending axially through the bottom of the tub and to which the 60 basket is engaged, means for reciprocating said shaft vertically carrying the basket therewith and a cover of reticulated material adjustably secured in the basket.

2. A washing machine embracing a tub, a 65 shaft extending through the bottom thereof, a basket rigidly secured on said shaft having closely arranged apertures in the sides and bottom thereof, a perforated cover rigidly secured on said shaft and fitted in said 70 basket, means adjustably supporting the cover at any distance from the bottom and means reciprocating said basket vertically in the tub.

3. A washing machine embracing a tub, a 75 vertically reciprocating basket therein having its sides and bottom formed of wire net, means reciprocating the basket vertically and a cover of reticulated material removable and adjustably engaged within the 80 basket.

4. A washing machine embracing a tub, a basket therein of wire net, a shaft extending axially through the bottom of the tub, and through the basket and to which the basket 85 is rigidly engaged, a crank for reciprocating said shaft and basket vertically, and a cover of reticulated material adapted to be engaged to said shaft within the basket and at any 90 distance from the bottom.

5. A washing machine embracing a tub, a shaft projecting through the bottom thereof, an apertured receptacle rigidly secured to the shaft in the tub, a cover for the receptacle rigidly secured to the same shaft with the 95 receptacle, means for adjusting the cover on the shaft and an eccentric mechanism for reciprocating said shaft.

6. In a washing machine a galvanized steel tub, a reciprocating shaft in the tub, a plurality of arms rigidly secured to the shaft, a 100 perforated receptacle secured on said arms, a perforated cover adjustable on the shaft, a shaft journaled transversely of the reciprocating shaft, operative connections between 105 the two shafts for reciprocating the first named shaft, and rotatable means for actuating the transverse shaft.

In testimony whereof I have hereunto subscribed my name in the presence of two 110 subscribing witnesses.

JESSE C. SIMMONS.
